JET-TYPE DRILLING JAR

Wilfred S. Crake, Kilgore, Tex., assignor to Shell Development Company, San Francisco, Calif., a corporation of Delaware

Original application December 28, 1948, Serial No. 67,708. Divided and this application November 18, 1952, Serial No. 321,136

2 Claims. (Cl. 255—27)

1

This application is a division of my copending application Serial Number 67,708, filed on the 28th day of December, 1948 now U. S. Patent No. 2,635,853.

This invention relates to a well tool and pertains more particularly to a jarring tool which may be lowered on a cable through a drill string for applying a jarring force to said drill string.

In drilling an oil well, it occasionally happens that the tubing or drill string becomes jammed in the well borehole by cavings of sand, formation debris or rock fragments falling into the borehole and wedging the drill string and drill bit attached thereto. The wedging materials around the bit or drill string are frequently compacted to such extent that circulation of drilling fluid cannot be relied upon to wash them away and release the bit. Accordingly, the bit or drill string can only be freed by applying a severe jarring action to the stuck member.

A tool commonly used is a mechanical jar adapted to be attached to the lower end of a drill string and run into the well, where it is connected to that portion of the drill string that is lodged in the well borehole. The mechanical jar permits a reciprocating or limited vertical movement of the upper part of the drill string, said reciprocating movement causing jarring action to the stuck portion of the drill string. The main disadvantage with this type of jar is that the drill string must be withdrawn from the well, equipped with the jar, and then reinserted into the well to be connected to the stuck section of drill string in the well.

The primary object of the present invention is to provide a jarring tool adapted to be lowered on a cable within a drill string and positioned in a stuck section of said drill string for engagement therewith.

Another object of this invention is to provide a cable jarring tool adapted to effect a jarring and strong uplifting action at the point, or close to the point, at which the drill string is stuck or wedged.

A further object of this invention is to provide a cable jarring tool adapted to impart a jetting effect to a well fluid within the drill string to aid or restore circulation within the well whereby said fluid may dislodge and wash away any materials that tend to immobilize the drill string.

Another object of this invention is to provide a jarring tool of simple and sturdy construction that is readily insertable into and removable from a drill string without the removal of any portion of said drill string.

2

Other objects and advantages of the present invention will become apparent from the following description, taken with reference to the drawing, wherein:

Figure 1 is a longitudinal view, partly in cross section, of the present jarring tool positioned within a rotary drill string.

Figure 2 is another view in cross section of the jarring tool of Figure 1, after an explosive charge carried by said tool has been detonated.

Figure 3 is a cross-sectional view of the present jarring tool incorporating a gas expandable anchoring means.

Referring to Figure 1, the present jet-type drilling jar 10 is shown in place inside a heavy drill collar 14 at the bottom of a drill string. In this case, cavings 20 have wedged the drill bit 15, carried at the lower end of the drill string, against the wall 19 of the well borehole. One or more apertures 16 in the drill bit form fluid outlet means whereby a drilling fluid may be circulated during drilling operations by pumping it down through the drill string 14, out the apertures 16 and upwards in the annular space 18 between the outer wall of said drill string and the wall 19 of the borehole.

The present jar 10 may be run into the well on a cable 11, preferably containing an insulated electrical conductor 38 for firing an explosive. It is to be understood that an ordinary cable or wire line may be used if mechanical devices are employed to ignite the explosive. In this embodiment the cable 11 is attached to a cable socket 39 and the electrical conductor 38 is run through or alongside a sinker bar 12 and a hammer-and-anvil type mechanical jar that may be interposed between the cable 11 and the tool 10 to aid in sinking the tool 10 in the well and in jarring it free from the surrounding drill string or collar 14. The electrical conductor 38 continues downward through the tool 10 terminating at a chamber 33 adapted to contain a detonating mechanism.

The jet-type jar 10 comprises a cylindrical body member 21, a portion 22 thereof having a reduced diameter. Carried on or integrally formed with said body member 21 is a slip bowl or multiple slip bowls 23 having outer tapered faces. Slidably mounted for limited longitudinal movement on said body 21 is a jar anchoring means which comprises a ring or sleeve 24 to which is attached, in any suitable manner, e. g., welding a plurality of vertically depending slip arms 25 which may be either hinged or made of flexible material whereby they may be spread

outwardly toward the inner wall of said drill string 14. The lower ends of the slip arms 25 are provided with gripping elements or slips 26 having toothed or serrated faces that are curved to conform to the inner surface of the drill string 14. The slips 26 are mounted in slideable engagement with the slip bowls 23, being normally held in their retracted position, as shown in Figure 1, by a tension spring 27. Pins 28 or other suitable fastening means secure the top of the spring 27 to the body member 21.

Removably affixed to the bottom of the body member 21, in any suitable manner, as by screw threads 31, is a thick-walled cylinder 29 having a central chamber 33 formed therein, which chamber contains suitable firing mechanism for igniting an explosive charge. A thick-walled housing 30, having an axial bore 31 therethrough, is secured by screw threads 32 to the lower end of cylinder 29. The axial bore 31 of said housing 30 forms a chamber in which a charge of explosive 34 may be carried. Chamber 33 containing an explosive cap or a firing mechanism (not shown) and chamber 31 housing the explosive charge 34 are interconnected by a suitable passageway 35. The lower end of the axial bore 31 may be tapered as at 36, if desired, to concentrate and focus the blast from the charge 34 when said charge is detonated.

Any suitable amount and type of explosive charge 34 may be used depending on the amount of jarring and lifting action desired. Preferably the explosive is a slow-burning type smokeless powder of the type used as a propellant charge for military purposes. It is desirable to use a waterproof type explosive as the borehole of the well is generally filled with fluid. Alternatively, an explosive charge covered with a waterproof material or carried in a waterproof container may be employed, said material or container being of an easily destructible and relatively thin material such as, for example, rubber, plastic, parchment, aluminum or other metallic foil, and the like.

When the present jarring tool is employed to jar free a drill string 14 with drill bit 15, the point at which the drill string is struck is previously determined by suitable means well known to the art, such as a magnetic tester. The jarring tool 10 is then attached to the end of the cable 11 and lowered through the drill string 14 to the level at which the drill pipe is stuck. In this case, the cavings 20 are illustrated as wedging the drill bit 15 in place against the wall of the well 19. Hence, the jarring tool 10 is lowered to a position just above the drill bit 15. In operation, the electrical conductor cable 11 may be attached to a suitable power source and switch means (not shown) at the surface. With the explosive carrying jarring tool 10 in place as shown in Figure 1, the firing mechanism or cap contained in chamber 33 is actuated or fired to igniting the explosive jet charge 34. The gases generated by the igniting charge 34 discharge downwardly through the axial bore causing the parts of the tool body 21, 22, 20 and 30 to move vertically upward.

The inertia of the spring-supported slip assembly, comprising ring 24, arms 25 and slips 26, causes it to stand momentarily substantially still whereby the spring 27 is extended and the slips 26 are caused to move outwardly as the backs of the slips slide over the faces of the rising slip bowls 23. The slips move outwardly until the teeth of the slips 26 engage the inside of

the drill string 14, as shown in Figure 2. Thus, the upward vertical movement of the tool body 21, 22, 29 and 30 is arrested and the remainder of the explosive thrust is transferred to the drill string 14 whereby said drill string is subjected to a sharp jarring and uplifting action. Prior to firing the explosive 34, the drill string is preferably subjected to a strong upward pull from the surface so that considerable tension exists in the drill string. The vertically-directed explosive reaction of the jet adds greatly and suddenly to this tension, helping to jar the stuck drill pipe free and causing the cavings 20 to be crushed or jammed into the borehole wall 19.

After the explosive force is spent, the weight of the tool body 21, 22, 29 and 30 is normally sufficient to disengage the slips 26 from the inner surface of the drill string 14 as the drilling jar is allowed to drop slightly. If this fails to disengage the slips 26, a mechanical jar 13 may be actuated by pull or release of the cable 11. Either action causes the slip bowl 23 to slide downwardly from the position shown in Figure 2 to that shown in Figure 1, whereby the slips 26 are disengaged. The spring 27 pulls the ring 24 and attached slip arms 25 and slips 26 into their retracted position (Figure 1) thus allowing the jarring tool 10 to be withdrawn to the surface by the cable 11.

An additional advantage of the present jarring tool is that the explosive discharge jetting-action may be utilized to restore circulation in a well borehole. It occasionally happens that circulation of drilling fluid down the pipe string 14, out the apertures 16 of the bit 15 and into the annulus 18, is blocked by cavings 20 in the annulus 18 above the drill bit. At such times, the pressure capacity of the mud pumps at the surface is usually not sufficient to cause the pumped fluid to wash these cavings 20 away and restore circulation. By using the present jet jarring tool and firing it immediately above the drill bit 15, a very high pressure is created inside the lower end of the drill string 14 which is sufficient to dislodge the cavings 20 and restore circulation in the well.

Another embodiment of the present jarring device is shown in Figure 3 wherein a portion of the gases, generated during the explosion, is utilized to expand the anchoring means carried by said device. Affixed to a sinker bar 12 which is in turn secured to the lower end of a cable 11 containing an electrical conductor, is a body member 50 having a recessed wall portion 51 adapted to house a plurality of anchoring slips 52. A plurality of lateral piston chambers 53 are formed in said recessed wall portion, said chambers being in communication with an axial bore 54 in said body member 50 which also serves as a chamber for housing detonating means or materials.

Slidably mounted for lateral movement in the piston chambers 53 in a substantially fluid-tight manner are a plurality of pistons 55 that are fixedly secured to the inner surfaces of the anchoring slips 52. The slips 52 are curved to conform with the inner surface of a surrounding drill string 56. The faces of the slips 52 are serrated or toothed for gripping the inner surface of the drill string 56 when expanded thereagainst. The electrical conductor 57 carried by the cable 11 extends through the sinker bar 12 and into the chamber 54 housing the ignition means (not shown).

Threadedly secured to the lower end of the

body member 50 is a housing member having an axial bore therethrough. The upper part 58 of the bore is enlarged to form a chamber for containing an explosive charge 59 while the lower portion 60 of said bore is shaped to direct the explosive blast downwardly.

In operation, the present jarring tool is lowered into a drill string 56 to a predetermined depth where the charge 59 is exploded in a manner previously described. A portion of the gases generated during the explosion is forced into the axial bore 54 of the body member 50. The pistons 55, in communication with said axial bore 54, are instantaneously forced outwardly by the gaseous pressure causing the attached slips 52 to contact the inner wall of the drill string 56, thus fixedly anchoring the tool in place during the time period required by the explosive bases to escape through the bore 60. It will thus be seen that upon the firing of the explosive charge 20 the drill string 56 is subjected to a sharp jarring and strong uplifting action in a manner similar to that described with regard to the apparatus of Figures 1 and 2.

I claim as my invention:

1. A jarring tool adapted to be lowered on a cable within a tubular string in a well, said tool comprising an elongated body member, a chamber in said body containing an explosive charge, means in communication with said chamber for exploding said charge, a downwardly extending passageway from said chamber to guide the explosive gases escaping therefrom, whereby an upward reaction thrust is developed to move said body member upwards, and anchoring means outwardly carried by said body member, radially expandible slips carried by said anchoring means,

a portion of the inner surfaces of said slips being in communication with said chamber and being actuated by a portion of escaping explosive gases to grip the inner walls of said tubular string, thereby imparting to said string a jarring upward thrust.

2. A jarring tool adapted to be lowered on a cable within a tubular string in a well, said tool comprising an elongated body member having an axial bore formed in the lower portion thereof and a plurality of lateral openings between said axial bore and the outside of said body member, a chamber forming part of the axial bore in said body containing an explosive charge, means in communication with said chamber for exploding said charge, a downwardly extending passageway from said chamber to guide the explosive gases escaping therefrom, whereby an upward reaction thrust is developed to move said body member upwards, and anchoring means outwardly carried by said body member, said anchoring means comprising a plurality of piston means mounted in a substantially fluidtight manner for limited lateral movement in said lateral openings, and gripping means affixed to said piston means and movable therewith, said anchoring means being actuated by a portion of escaping explosive gases to grip the inner walls of said tubular string, whereby said upward thrust is transmitted to said tubular string.

WILFRED S. CRAKE.
